UNITED STATES PATENT OFFICE.

LEVI BURNELL, OF MILWAUKEE, WISCONSIN.

IMPROVEMENT IN WATER-METERS.

Specification forming part of Letters Patent No. 25,948, dated November 1, 1859.

To all whom it may concern:

Be it known that I, LEVI BURNELL, of Milwaukee, in the county of Milwaukee and State of Wisconsin, have invented a new and Improved Water-Meter; and I do hereby declare that the following is a full, clear, and exact description of the same, reference being had to the accompanying drawings, making a part of this specification, in which—

Figure 1 is a transverse vertical section of my invention, taken in the plane indicated by the line y y , Fig. 2. Fig. 2 is a horizontal section of the same, the line x x , Fig. 1, indicating the plane of section.

Similar letters of reference in both views indicate corresponding parts.

This invention relates to that class of water-meters in which a bucket-wheel is employed, which is caused to rotate by the gravity of the water as it enters one of the buckets after the other; and it consists in arranging the induction-pipe, which also forms a gudgeon or arbor, around which the bucket-wheel rotates, with a narrow slot, in combination with lips formed by the inner edges of the buckets, in such a manner that when one of the buckets is filled to the required height the water is cut off instantaneously and made to flow into the next succeeding bucket; and my invention also consists in the arrangement of a counterpoise, in combination with stops on the outside of said bucket-wheel, whereby the wheel is arrested until the weight of the water in the filling-bucket is able to overcome the counterpoise, when the latter is raised and the next succeeding bucket brought into action. By these means the water in the buckets is made to rise to a uniform height, and it is not only measured correctly, but also weighed at the same time.

To enable those skilled in the art to make and use my invention, I will proceed to describe it.

The bucket-wheel A rotates on a hollow arbor, B. This arbor is stationary, one end of the same being firmly secured to a plate, C, that is fastened to the frame or chamber in which the wheel operates. The arbor fits loosely into the wheel, and one side of the same rests on friction-rollers a. The other side of the wheel forms a tubular projection, b, which turns on a pivot, c, that extends from the hol-

low arbor, being supported by a pendant, d. A pinion, e, which is secured on the tubular projection b of the wheel, serves to transmit the motion of the latter to the registering mechanism. The space inclosed by the rim and sides of the wheel is divided into four (more or less) buckets, D, which are furnished with two openings, f and g, one to receive and the other to discharge the water. The edges of the inlet-openings f are bent up, forming lips h, that nearly touch the outside of the arbor B. The form of the buckets D is such that the water, as it enters one after the other, causes the wheel A to rotate simply by its gravity and independent from the head under which it enters. Water is admitted to the hollow arbor B by a tube, i, and a narrow slot, j, serves to bring the water to the buckets. If the wheel were now left to itself, a comparatively small quantity of water admitted into each bucket would be sufficient to cause the wheel to rotate. It is necessary, therefore, to make provision to arrest the wheel until each bucket fills to a certain uniform height. This object I have effected by placing stops k on the outside of the wheel, which strike against one arm of a bell-crank lever, E, from the other arm of which a counterpoise, F, is suspended. That end of the bell-crank which retains the wheel is furnished with a friction-roller, l, and the weight of the counterpoise is such that it arrests the wheel in the position shown in Fig. 1 until the bucket under the slot j is filled up to the required height. The weight of the water is now sufficient to overcome the counterpoise F, the stop passes the friction-roller l, and the next succeeding bucket comes into action. All this takes place instantaneously, and the lips h on the inner edges of the buckets as they pass the narrow slot j cut off the water from each bucket so quick that no perceptible fault can occur.

By the arrangement of stops k and of the counterpoise F the water is not only measured correctly, but it is also weighed, so that a meter constructed according to my invention will give a more correct result than any meter heretofore used.

It is of course necessary to inclose this meter in an air-tight chamber, from the bottom of which the water is distributed, so that the pressure of the air in the upper part of the chamber which is occupied by the meter coun-

terbalances the head of the water. This chamber forms at the same time a protection to the working parts of the meter.

Having thus fully described my invention, what I claim as new, and desire to secure by Letters Patent, is—

The arrangement of the hollow arbor B with

a narrow slot, *j*, in combination with the lips *h*, formed by the inner edges of the buckets *D*, substantially as and for the purpose specified.

LEVI BURNELL.
